STIMULATOR

Joseph C. Hinsey, Scarsdale, and William A. Geohegan, Mamaroneck, N. Y., assignors to the Government of the United States

Application May 16, 1945, Serial No. 594,046

3 Claims. (Cl. 128—421)

1

This invention relates generally to stimulating apparatus but more particularly to a neurological stimulator designed primarily for use in the operating room when it is desired to stimulate various parts of the nervous system either as a means of exploration or in experimental work.

One object of the invention is to provide a stimulator in which the nature and strength of the stimulus can be accurately controlled and duplicated whenever necessary.

Another object of the invention is to provide a stimulator which operates on an alternating current of constant frequency and wave form.

Another object of the invention is to provide a device of the class described which provides a stimulus of constant uniform strength.

A further object of the invention is to provide a stimulating device of the class described which is of simple construction and which may be easily operated with a maximum of safety.

With these and other objects in view, the invention consists of the construction and the combination of parts as well as of the detail and arrangement of parts as will be more particularly set forth in the specification relative to the accompanying drawings.

Referring to the drawings in which like parts are indicated by similar reference characters:

Figure 1 is a perspective view showing the entire apparatus mounted in a container having side compartments for the connecting cords;

Figure 2 is a plan view showing the under surface of the lower panel and the arrangement of the various electrical elements thereon;

Figure 3 is a perspective view of the fuse housing showing the fuses, a lower portion of the power switch and filters; and

Figure 4 is a diagrammatic view showing the electrical circuits of the apparatus.

Briefly stated, the device comprises a stimulator which is operated by the ordinary house current, and which furnishes uniform stimulation at a predetermined voltage, wave form and frequency.

It is frequently important that the surgeon know the effective strength of the stimulus he is delivering, for example, if he stimulates a motor nerve central to an injury and fails to elicit a response from the muscles it is important that he know whether this failure of response is due to nerve injury or to an inadequate stimulus. It is further important that the stimulus be such that its nature and strength can be accurately recorded and duplicated by other workers.

Much of the previous work of stimulation has been done with the Harvard Inductorium. With

2

this apparatus, wave form and frequency are subject to wide variation from day to day and even from minute to minute. The voltage delivered varies widely with the resistance of the tissues stimulated and may also change materially as the battery ages. Thyratron and similar stimulators supply relatively uniform frequency and wave form over a short period but do not hold their calibration well. In addition, the voltage delivered under no-load conditions is apt to be much higher than that under actual stimulating conditions and for accurate results the voltage must be measured by means of a cathode ray oscilloscope or vacuum tube voltmeter during stimulation. Sixty cycle sine wave stimulators have been used previous to this invention but in general, while they may be safe for use by someone familiar with their construction, they are not safe for use routinely by surgeons not familiar with electrical apparatus.

Effectiveness of a stimulus depends upon frequency, wave form and voltage delivered at the electrodes during stimulation. Frequently, reported results of stimulating various parts of the nervous system are of little or no value to other workers because the conditions of stimulation are not stated completely or accurately. For example, the voltage may be stated without mention of whether it was measured at no-load, or during stimulation, and in the case of stimulators with high source-impedance, there may be a wide difference between the two. Where a sine wave stimulus was used, it is frequently not clear whether it was measured in root mean square volts, or peak-to-peak volts. It is seldom convenient to measure all characteristics of the stimulus in the operating room. The instrument described herein, which is designed to operate from 100-120 volt, 50-60 cycle power lines, derives the stimulus directly from the power source, and the voltmeter for the range in use (which reads in R. M. S. volts) is connected directly across the electrodes. It is necessary, therefore, only to read the voltmeter during stimulation to present a clear statement of the stimulus employed. An appropriate statement would be as follows: "The stimulus employed was a sixty cycle sine wave at 1.6 R. M. S. volts, measured under load."

The instrument has a low source-impedance so that the voltage under load will ordinarily deviate only slightly from the no-load setting.

To assure safety in the operation of the device, the line voltage is passed through two transformers before application to the patient to prevent direct contact with the line even in the event

of insulation breakdown in one transformer. Power supply leads have been isolated in a Bakelite compartment to prevent their direct contact with the output circuit even in the event of breakage of one of the wires. In the opinion of the designers, this instrument is safer from the standpoint of accidental shock than are most electrical instruments used in operating rooms.

The device is adapted for use with a high and a low range of voltages. The low range will be adequate for most work, and should be used wherever possible. The high range is intended primarily for stimulation of the sensory cortex where 15-20 volts may sometimes be required. The high range should not be used on the motor cortex.

To furnish power supply, the instrument may be plugged directly into any 100-120 volt, 50-60 cycle A. C. outlet. It may be operated from 200-240 volt supplies by the use of an appropriate step-down auto-transformer. The power supply ground is used to dissipate static charges. The instrument should, therefore, be used on power supplies which have one side grounded, and the step-down transformer, if used, should be of the auto-transformer type.

The instrument is protected by one-ampere fuses, mounted beneath the panel. These should blow only if the instrument itself develops a defect, or if it is plugged into the wrong type of power supply. Access to the fuses may be obtained by removing the six front-panel screws, and lifting the panel out of the case. Spare fuses are provided, and will be found in clips near the working fuses.

The apparatus includes an input circuit and an output circuit which are inductively coupled by two transformers. Referring to Fig. 4, which shows a diagrammatic outline of the circuits, the numerals 10 and 11 indicate the terminals of a plug 12 which is adapted to be inserted into a wall socket or other connection to couple the apparatus to the usual 110 volt A. C. current supply. The terminal 10 is connected through the conductor 13 to fuse 14 which in turn is connected through conductor 15 to the terminal 16' of the primary coil 16 of the transformer 17. The other plug terminal 11 is connected through conductor 18, fuse 19, conductor 20, switch 21 and conductor 22 to the terminal 23 of the primary coil 16. The numeral 24 indicates the secondary coil of the transformer 17. The terminals 25 and 26 of the secondary coil 24 are connected through conductors 27 and 28 to terminals 27' and 28' of primary coil 29 of the transformer 30. The transformer 30 is provided with a split secondary coil 31 which is provided with terminals 32, 33 and 34 and which functions to effect a greater and a lesser degree of stimulation as will be further described. The major portion of the split secondary coil 31 is connected to terminals 32 and 33 which in turn are connected respectively to switch terminals 35 and 36. The terminal 34 of the minor portion of the split secondary coil 31 is connected to the fixed resistance 37.

To place a portion of the secondary coil 31 or the entire secondary coil in the stimulating circuit a switch 38 is provided. This switch is of the cam operated type and provided with two blades 45 and 44 which are adapted to contact simultaneously, either the terminals 36 and 39, or terminals 35 and 40.

The fixed resistance 37 is connected between the terminal 34 of the secondary coil 31 and the terminal 41 of a variable resistance 42 of a rheo-

stat 43 (see Fig. 2). The other end of the variable resistance 42 is connected to the switch blade 44. The switch blades 44 and 45 of the switch 38 are connected by a conductor 46 which in turn is connected through conductor 47 to switch blade 48 of the magnetic switch or relay 49 as will be further explained.

It will be noted that the switch blade 44 is adapted to contact the switch terminals 35 and 36, and switch blade 45 is adapted to contact switch terminals 39 and 40. These blades 44 and 45 operate simultaneously so that by setting the blades on the desired pair of contact terminals the circuit may be completed through either the terminals 36 and 39 or the terminals 35 and 40.

The switch blade 50 of the rheostat 43 is connected through conductor 51 to switch blade 52 of an electromagnetic switch or relay 49. The switch blades 48 and 52 of the relay, when actuated by energization of magnet 53 thereof, contact terminals 54 and 55, and connect the leads 47 and 51 through conductors 56 and 57 to the two applicator electrodes 58 and 59 of the hand-piece 60. The conductors 56 and 57 are bridged by a resistance 56' and a resistance 57' is connected from conductor 51 to conductor 51.

The magnetic switch on relay 49 comprises a central magnetic core wrapped by a coil 61 connected to the terminals 62 and 63. The terminal 62 is connected through conductor 64 to the terminal 65 of the push button switch 66 and the terminal 63 is connected through the conductor 67 and thence through conductors 68 and 27 to terminal 25 of the secondary winding 24 of the transformer 17. The other terminal 69 of the switch 66 is connected to terminal 26 of the secondary winding 24 of the transformer 17 by means of conductors 70 and 28.

In order to energize the magnet 53, the button 71 of the push button switch is pressed inwardly thus spreading apart the contact members 72 and 73, which are connected by conductor 73', until they are in contact with the stationary contact members 74 and 75, allowing current to pass through the conductively connected contact members 72 and 73 to thus complete the circuit from the power lines 27 and 28 through the coil 61.

The filament terminals 77 and 78 of a pilot lamp 79 are connected to the conductors 68 and 70 so that the lamp remains lighted so long as the instrument is plugged into a source of power and the power switch is turned on.

The conductors 47 and 51 which are adapted to be connected to the electrodes to furnish the desired stimulation may be bridged by either of two voltmeters which are designated by the numerals 80 and 81, depending on the setting of blade 45 of switch 38. Of these voltmeters, 81 is for a high range measurement and 80 for a low range. When bridging voltmeter 81 across the lines 47 and 51, the connections are through conductor 46, switch blade 45, conductor 82, voltmeter 81, conductor 83 to conductor 51, and when bridging voltmeter 80 across the lines 47 and 51 the connections are through conductor 46, switch blade 45, conductor 84, voltmeter 80, conductor 85 to conductor 51.

Five filters, each consisting of a condenser and a resistance are used to filter out high frequency currents which may be picked up by the line from generators, X-ray, radio apparatus, and similar sources of interference. Filter 86, consisting of resistance 87 and condenser 88, is inserted in the return line designated by the numerals 89 and

90; filter 91, consisting of resistance 92 and condenser 93, is inserted between conductor 15 and conductor 90; and filter 94, consisting of resistance 95 and condenser 96, is inserted between conductors 22 and 90. Filters are also inserted in the output circuit in proximity to the stimulating electrodes and the relay. Filter 97, consisting of resistance 98 and condenser 99, bridges conductors 67 and 51, it being connected to conductor 67 by conductor 100, and filter 101, which comprises resistance 102 and condenser 103, is inserted between conductors 47 and 100, the latter being connected to conductor 67. The foregoing resistances along with resistances 56' and 57' provide a leakage path for dissipation of static charges so that such charges cannot collect on the electrodes.

A foot switch (not shown) may also be used to control the circuit of the electrodes. Terminals 104 and 105 for connection of a foot switch are therefore provided.

The apparatus is contained within a casing 106 which is divided into a main central compartment 107 and two small side compartments 108 and 109 which are provided for retention of the input and electrode conductors 13 and 18, and 56 and 57, respectively. The various elements of the apparatus are attached either to an upper panel 110, a lower panel 111 or the side walls 112 and 113 which, with the lower panel and the front and a side wall of the casing, form a small insulated compartment to enclose the fuses 14 and 19, power switch 21, and filters 91 and 94. The spaced upper and lower panels 110 and 111, as shown in Fig. 3, provide for the better arrangement and protection of the wiring between the various parts of the apparatus.

The casing or cabinet is provided with a hinged lid, a carrying handle, and locks so that the apparatus may be readily transported and protected.

Having thus described our invention, what we claim as new and wish to secure by Letters Patent is:

1. A stimulator of the class described comprising an input circuit, high frequency filters associated with said input circuit and means for connecting said circuit to a source of alternating current of predetermined voltage, wave form, and frequency, having one side grounded, a transformer circuit including input and output transformers provided with primary and secondary coils, an output circuit, high frequency filters associated with said output circuit, applicator electrodes included in said circuit, means for selec-

5 tively connecting said output circuit with groups of secondary coils of said output transformer, meters for measuring high and low range voltages bridging said coil groups, a switch circuit connected with said transformer circuit, an electromagnetic switch and a manually operated switch included in said output circuit adapted to control the operation of said electrodes.

2. A stimulator of the class described comprising an input circuit, high frequency filtering means associated with said input circuit and means for connecting said circuit to a source of alternating current of predetermined voltage, wave form, and frequency, having one side grounded, a transformer circuit including input and output transformers provided with primary and secondary coils, an output circuit, high frequency filtering means associated with said output circuit, applicator electrodes included in said circuit, a switch circuit connected to said transformer circuit, a two-way switch connected to said output circuit, said switch adapted to selectively connect said output circuit with groups of secondary coils of said output transformer, a high frequency filter associated with said switch circuit, meters for measuring high and low range voltages bridging said coil groups, an electromagnetic switch, and a manually operated switch included in said output circuit adapted to control the operation of said electrodes.

3. A stimulator of the class described comprising an input circuit, high frequency filters associated with said input circuit and means for connecting said circuit to a source of alternating current of predetermined voltage, wave form, and frequency, a transformer circuit including an input transformer provided with a primary and a secondary coil and an output transformer provided with a primary and a split secondary coil, said split secondary coil being adapted to provide a greater and a lesser degree of stimulation, an output circuit, high frequency filters associated with said output circuit, applicator electrodes included in said circuit, means for selectively connecting said output circuit with groups of secondary coils of said output transformer, meters for measuring high and low range voltages bridging said coil groups, a switch circuit connected with said transformer circuit, an electromagnetic switch and a manually operated switch included in said output circuit adapted to control the operation of said electrodes.

JOSEPH C. HINSEY.
